UNITED STATES PATENT OFFICE.

JOSEPH TREMBLAY, OF ST. CUNEGONDE, CANADA, ASSIGNOR TO TREMBLAY & LYMBURNER, (JOSEPH TREMBLAY AND MARIE LOUISE DEXTRAS DIT BEZIER, WIFE OF LOUIS MARCEL LYMBURNER,) OF ST. CUNEGONDE, CANADA.

VALVE.

SPECIFICATION forming part of Letters Patent No. 694,502, dated March 4, 1902.

Application filed March 15, 1901. Serial No. 51,404. (No model.)

To all whom it may concern:

Be it known that I, JOSEPH TREMBLAY, a subject of His Majesty the King of Great Britain, residing at St. Cunegonde, in the county of

5 Hochelaga, Province of Quebec, Canada, have invented certain new and useful Improvements in Valves; and I do hereby declare that the following is a full, clear, and exact description of the invention, such as will enable 10 others skilled in the art to which it appertains to make and use the same.

My invention relates to improvements in valves especially adapted for use on street-hydrants and fire-plugs; and the primary object 15 of the invention is to provide a quick-opening valve adapted to be easily moved to a fully-open position by a partial turn of a wrench or other implement.

Further objects of the invention are to simplify 20 the construction, enable the device to be easily and quickly applied to a hydrant or other structure, to permit the free and unobstructed passage of the water when the valve is opened, and to make the valve durable, 25 efficient, and safe in service.

A further object of the invention is to provide for the admission of air to the hydrant, with a view to minimizing the tendency of the hydrant-valve to become frozen in cold 30 weather.

My improved valve is intended to take the place of the cut-off valve usually provided in fire-hydrants; but said valve is free from the practical objections that exist in the use of 35 the cut-off, because any one of the series of valves with which a hydrant is equipped can be brought into service without interrupting any of the other valves. Furthermore, the improved valve provides for the ready coupling 40 of a line of hose to the slidable valve element, which during the coupling operation is in a state of rest owing to the pressure of water against the valve-head and the frictional resistance that exists between the engaging 45 parts; but when the hose-coupling becomes tightly screwed up to the valve element the latter is given the necessary axial motion, and such motion is translated into the slidable endwise movement required to open the 50 valve, the whole operation requiring only a few moments' time. Furthermore, the valve is packed against leakage in both its open

and closed positions, such leakage in the open position of the valve being especially advantageous, because it obviates reduction of the 55 water-pressure.

With these ends in view the invention comprises a bearing-ring, a valve-seat, a valve-head, and a slidable tubular valve element, 60 said tubular valve element and the bearing-ring having engagement one with the other, whereby rotary motion communicated to the tubular valve element imparts a quick sliding movement to the same to open or close the valve-passage. 65

The invention further consists in the novel construction and arrangement of parts, which will be hereinafter fully described and claimed.

In the drawings hereto annexed, forming a 70 part of this specification, Figure 1 is a sectional elevation through a portion of a hydrant, illustrating one means for securing my improved cut-off valve in position thereon, the valve being shown in elevation and in its 75 closed position. Fig. 2 is a longitudinal section through the valve, the same being represented in its open position. Fig. 3 is a detail view of the slidable valve element removed from the stationary bearing-ring. Fig. 80 4 is a cross-section through the valve in the plane of the dotted line 4 4 on Fig. 2. Fig. 5 is a longitudinal section through another 85 form of valve embodying my invention. Figs. 6 and 7 are enlarged detail sections through 90 a valved air-inlet which is adapted to normally remain open when the valve is not in service for the purpose of supplying air to the inside of the hydrant, said inlet-valve being shown in its open position by Fig. 6 and 95 in its closed position by Fig. 7.

The same numerals of reference indicate like parts in each figure of the drawing.

10 designates a part of the hydrant or street-plug, which is provided with the usual nipple 95 11. The improved cut-off valve which I have invented may have its stationary element secured to this hydrant-nipple in any approved way—as, for example, by screwing a threaded part of the valve into a threaded 100 nipple or by a fused-metal joint. The stationary part of the valve is embodied in a bearing-ring 12, which is provided with the external parallel collars 13 14, adapted to be

positioned in the hydrant-nipple so as to occupy a practically flush relation therewith. This bearing-ring is provided between said collars with the radial lugs 15, and said ring is adapted to be secured within the nipple 11, so as to produce an annular space into which fused metal may be run, so as to form the joint-filling 16. This fused metal fills the annular space and encompasses the lugs 15 and the collars 13 14, whereby the bearing-ring is solidly united to the hydrant against any possibility of displacement. This bearing-ring is reduced at its inner extremity, so as to form a narrow annular valve-seat 17 at the inner or rear portion of said ring, said valve-seat lying within the hydrant and adapted for engagement by the valve-head on closure of the latter. The front end of the bearing-ring 12 is exposed beyond the hydrant-nipple and is likewise reduced, so as to form a narrow annular seat 18 at the front edge of the bearing-ring. Said bearing-ring is formed with a coarse multiple female thread 19, which is formed in the inner surface of the ring and is adapted to have its terminals lie at the front and rear ends of said ring, so as to properly engage with a similar male thread on the slidable and revolvable valve element 20. Said valve element is essentially tubular or hollow, and it is provided with the coarse multiple male thread 21, arranged to have engagement with the female thread 19 of the bearing-ring, whereby the two threads are adapted to coact to give endwise movement to the valve element when a partial rotation is given thereto. This tubular valve element is provided with an external collar 22 and with a front threaded extremity 23, the latter adapted to receive the metallic threaded hose-coupling familiar to those skilled in the art. The collar 22 of the tubular valve element has the studs 24, adapted for engagement by a wrench or other implement in the hands of a fireman, and said collar is provided on its inner face with an annular groove 25, the same receiving a soft-metal packing 26, which occupies such relation to the seat 18 on the stationary bearing-ring that the parts 18 26 are adapted to firmly engage when the tubular valve element is moved endwise to its open position, as shown by Fig. 2, whereby leakage of water through the space between the tubular valve element and the bearing-ring is wholly prevented.

55 The tubular valve element is provided on its inner end with the short legs 27, united by a threaded ring 28 and arranged to form a series of ports 29, through which ports the water is adapted to pass on opening the valve so as to make its exit through the tubular valve element 20. The threaded ring 28 provides for the attachment of the valve-head 30, the latter having an annular flange 31, which is interiorly threaded in order that the ring 28 may be screwed thereinto, whereby the valve-head has a slidable connection with the slidable tubular valve element. Said

valve-head is formed with an annular groove 32 in the inner edge or face of its annular flange 31, which groove receives a soft-metal packing 33, that lies opposite to and concentric with the valve-seat 17 at the rear extremity of the bearing 12, whereby the parts 17 33 are adapted to have such firm engagement as to produce a water-tight joint around the valve-head when the valve is adjusted to its closed position, as represented by Fig. 1.

In the service of the fire hydrant or plug either of the series of cut-off valves may be opened without disturbing or interrupting the service of any one or more of the valves to which lines of hose are attached. It is only necessary for the fireman to screw the hose-nipple onto the threaded end 23 of the tubular valve element, the latter being at this time in its closed position and exposed to the pressure of the water which is contained in the open fire-hydrant. The pressure of the water on the valve-head and the frictional engagement of the tubular valve 90 with the bearing-ring is sufficient to maintain said tubular valve element in its closed position during the operation of applying the hose-coupling thereto; but when the hose-coupling is screwed up tight at the completion of the coupling operation the frictional resistance and the pressure of the water on the valve-head is overcome, whereby a partial turn is given to the tubular valve element, and this rotary motion is translated into reciprocating motion by the coacting male and female threads. This endwise movement of the tubular valve element carries the valve-head away from the seat 17 and projects the valve element into the hydrant, so as to expose the ports 29, through which the water is free to pass into and through the tubular element 20 and thence to the hose. The operation of closing the valve is easily and quickly performed, because the partial turn necessary to give the endwise movement to the valve may easily be effected at the time of unscrewing the hose-coupling or subsequent thereto. In either the closed or open position of the valve the soft-metal packings maintain tight joints, which effectually minimize the leakage of water.

In the embodiment of the invention represented by Fig. 5 the construction of the parts are reversed in some particulars. The stationary bearing-ring 12 is provided with inwardly-extending legs 34, to which is secured the stationary valve-head 35, said legs arranged to form the ports 29. The valve-head is provided within the annular circle of the legs 34 with a soft-metal packing 36, which is secured in a groove formed in the inner face of the valve-head. Instead of forming slots or openings in the tubular element 37 the latter is made in a single continuous tube arranged to fit slidably and removably in the bearing-ring and to present its inner edge in the closed position of said valve element against the packing 36, whereby the solid in-

ner end of the tubular element is arranged to fit across the ports 29 of the bearing-ring, and thereby effectually cut off the passage of water. The tubular element 37 has the collar 38 removably screwed thereon; but in all other respects the valve shown by Fig. 5 is substantially the same as heretofore described.

It is desirable to equip the fire-hydrant with means for admitting air to the interior thereof, whereby the valves of the hydrant are prevented during cold weather from freezing. I contemplate the equipment of my improved cut-off valve with an automatic air-vent valve; but in this connection it is proper to state that it may be necessary to equip only one of a series of cut-off valves provided in a fire-hydrant with such an automatic air-vent. One or more of the air-vent valves may be provided in the cut-off valve; but I have shown only one vent-valve applied in Figs. 6 and 7. A radial hole 39 is provided in the exposed part of the tubular valve element, preferably through the annular collar 22 thereof. Into this hole is screwed a male-threaded bushing 40, the same arranged for its inner and outer portions to have flush relation with the inner surfaces of the valve element and with the external face of the collar, and this bushing is provided on its inner end with a valve-seat 41. The bushing, furthermore, is counterbored to form the shoulders 42 43, and said bushing receives a tubular valve-stem 44, the latter having the valve-head 45 at its inner end, said valve-head adapted to occupy the seat 41. The tubular valve-stem forms an air-admission passage which communicate with the radial ports 46, that are adapted in the open position of the valve to permit the air to flow into the tubular valve element. The valve-stem has a suitable guide-pin 48, that plays in the slot of the bushing, and on said stem is a stud or pin 47, that constitutes a seat for one end of a coiled spring 49, said spring being seated against one of the shoulders 42 of the bushing. In the normal position of the vent-valve the valve-head is pressed by the spring away from the valve-seat in order to open the air-passage for the admission of air into the interior of the cut-off valve; but when said cut-off valve is in service and water is passing through the tubular valve elements 20 or 37 the pressure of the water against the vent-valve head 45 forces the latter to its seat 41, thereby closing the vent-opening.

Changes within the scope of the appended claims may be made in the form and proportion of some of the parts while their essential features are retained and the spirit of the invention is embodied. Hence I do not desire to be limited to the precise form of all the parts as shown, reserving the right to vary therefrom.

Although I have shown and described the coarse engaging threads on the bearing-ring

and the tubular element, I do not desire to strictly limit myself to this construction, because I am aware that these parts may be united by an ordinary thread-joint. This, however, will require several turns of the valve element, which is objectionable because of the tendency to twist the hose; but in my improved construction said objections are overcome, because the engaging threads only require the tubular element to be given a half-turn.

I claim—

1. In a valve of the character described, the combination of a bearing-ring, a hollow one-piece slideable member which exceeds the bearing-ring in length and is provided at one end with a hose-attaching nipple which is normally exposed beyond the front end of the bearing-ring, a valve-head in operative relation to the inner end of the hollow member, and metallic packings coöperatively disposed to the inner and outer portions of the bearing-ring and the hollow member and arranged to minimize leakage through and between the members of the valve in the opened and closed positions thereof, substantially as described.

2. In a valve of the character described, the combination in a single structure of the following instrumentalities, to wit: a bearing-ring, a hollow one-piece slideable member which exceeds the bearing-ring in length and is provided at one end beyond the front of the bearing-ring with the exposed operating-collar and with the hose-attaching nipple, a packing attached to the exposed collar and adapted to seat itself against the bearing-ring on adjustment of the hollow member to one position, a valve-head in coöperative relation to the inner portion of the hollow member, and another packing arranged to tightly close the joint between the bearing-ring and the hollow member when the valve is adjusted to its other position; the two packings coöperating with the members of the valve to minimize leakage through the valve and between the members thereof in the opened or closed positions of the same, substantially as described.

3. In a valve of the character described, the combination of a bearing-ring provided at its exposed front portion with a seat, a hollow one-piece slideable member which exceeds the bearing-ring in length and is provided beyond the front portion of the bearing-ring with an exposed operating-collar and with a threaded hose-attaching nipple, a metallic packing seated in the rear face of said collar and in coöperative relation to said seat of the bearing-ring and adapted to occupy the same when the valve is moved to an open position, and a valve-head coöperating with said hollow member, substantially as described.

4. In a valve of the character described, the combination of a bearing-ring provided at its front and rear ends with the seats, a hollow one-piece slideable member which exceeds the bearing-ring in length and is provided at

- points beyond the front seat of the bearing-ring with an exposed collar and with a hose-attaching nipple, a valve-head movable with said hollow member, and metallic packings 5 mounted respectively in the exposed collar and in the valve-head and disposed in coöperative relation to the seats of the bearing-ring to engage alternately therewith, whereby one packing closes the valve tightly when 10 adjusted to a closed position and the other packing excludes leakage between the bearing-ring and the hollow member in the open position of the valve, as set forth.
5. In a valve of the character described, a 15 slidable tubular member provided at its inner end with spaced arms united by a threaded ring and at its outer end with an exposed collar and with a hose-attaching nipple, and a valve-head screwed to said threaded ring and 20 provided in one face with an annular packing which surrounds the tubular member, in combination with a bearing-ring having seats at its ends, and a packing mounted in the collar and adapted to one of the seats, the

whole being arranged for service in the man- 25 ner and for the purposes set forth.

6. A valve of the character described comprising a bearing-ring provided with an annular collar and with a series of lugs, a soft-metal filling-joint surrounding the bearing- 30 ring, a tubular valve element having threaded engagement with said bearing-ring, and a valve-head, as and for the purposes described.

7. A valve of the character described having 35 a tubular member provided with a collar, and a vent-valve supported within said tubular member, said vent-valve being normally open for the admission of air to the valve and adapted to be closed by the pressure of fluid 40 when the valve is opened, as and for the purposes described.

In witness whereof I have hereunto set my hand in the presence of two witnesses.

JOSEPH TREMBLAY.
